UNITED STATES PATENT OFFICE.

FRANÇOIS BAVEREY, OF LYON, FRANCE, ASSIGNOR TO SOCIETE DU CARBURATEUR ZENITH, OF LYON, FRANCE, A CORPORATION OF FRANCE.

CARBURETOR.

Application filed July 13, 1916. Serial No. 109,089.

To all whom it may concern:

Be it known that I, FRANÇOIS BAVEREY, a citizen of the French Republic, residing at Lyon, in France, have invented certain new and useful Improvements in Carburetors, of which the following is a full, clear, and exact description, reference being had to the accompanying drawings, forming part of this specification, in which—

10 Figures 1, 2 and 3 are diagrammatic views illustrating the different forms of carburetors embodying my invention;

Figure 4 is a plan view taken partly in section through a commercial carburetor having the characteristics illustrated in Figure 3; and

Figure 5 is a developed vertical section taken on the line VI—VI of Figure 4.

My invention relates broadly to carburetors, and more particularly those of the double Venturi type. It is designed to provide a simple and efficient device which will give the proper mixture at widely varying speeds, suction and loads under such conditions as those existing on automotive vehicles.

Referring more particularly to the form of carburetor illustrated particularly in Figure 1, there is a main venturi V and a secondary smaller venturi v placed coaxially in the air passage of the main venturi with its intake B outside the main venturi and its discharge end within and preferably beyond the most restricted part 35 of the same, where the vacuum is substantially at a maximum.

The fuel passage E enters the smaller venturi laterally through its side and preferably in the region of highest vacuum therein. In this form, the passage E has an air inlet G, which may be adjusted by a suitable valve R, to vary or modify the flow of fuel therethrough; and the liquid fuel flow is controlled by a constriction K in a vertically 45 extending collecting chamber exterior of the venturi and connected at its lower portion to the constant level reservoir indicated in the drawings to the right.

Figure 2 illustrates another construction, in which the fuel emulsion, automatically proportioned, is furnished by a submerged nozzle L, placed near the bottom of a well H, which is open at the top through a calibrated or restricted orifice I. The collecting chamber J delivers the emulsion to

the passage E, which may or may not be open to the atmosphere at G. The chamber J may have any length desired, and the constant level supply, the submerged nozzle, and the well may therefore be placed at some distance from the main air passage and throttle valve, as more fully explained in my United States Patent No. 1,259,072 of March 12th, 1918. The use of the double venturi permits the use of a long chamber J, because there is a comparatively high vacuum at D where this conduit opens.

In Figure 3 there is shown another modification, in which the emulsion-producing means consists of a nozzle K and a relatively constant flow nozzle L, leading into a passage having an atmospheric well, both being connected to conduit E, having an air inlet G and an air control valve R.

Figures 4 and 5 show the construction of a carburetor having the suction-controlled nozzle and substantially constant flow nozzle shown diagrammatically in Figure 3. As shown in these figures, the main Venturi tube V is disposed horizontally. Co-axially with the main venturi is placed the secondary venturi v, held in position by a screw b. At the point D of about maximum vacuum in the small venturi is a circular groove a, so arranged that the fuel emulsion coming from the channel E is practically uniformly spread around the wall of the small venturi.

The nozzle K, controlled more by suction, which for convenience is made with the restricted passage or calibration at its lower end, communicates with the channel E having a regulable opening G to the atmosphere, which opening is controlled by means of screw i. The submerged nozzle with more nearly a constant flow is indicated at L at the bottom of the well H. Air enters through the openings O and carries the liquid fuel between the tube T and the inner surface of the well H, and is carried to the secondary venturi through the channel E. Small holes e through bottom part of the tube T facilitate the carrying of the liquid fuel by the air at times when there is a very low suction, when the well H is partially filled with liquid. A slow speed device is indicated at M, leading to the supply passage at the throttle and is similar to that shown in my United States Patent No. 1,186,371 of June 6, 1916.

In all of the forms shown, the fuel follows the surface of the small venturi and emerges therefrom in the shape of a hollow cone, the fuel stream being very thin and having air on both its inner and outer surfaces. Since the air and fuel move in parallel streams, eddies and consequent loss of head are obviated. On the other hand, as the taper of the secondary venturi is very slight, the parts followed by the fuel stream is only very slightly conical, with the result that the fuel remains in the central portion of the carburetor without condensation on the surface thereof.

The invention is not limited to the forms shown, but may be embodied in other structures within the scope of the claims.

I claim:

1. In a carburetor, a carbureting chamber having an air inlet, and a mixture outlet, a throttle valve in said outlet, a constant level chamber supplying liquid fuel, a fuel nozzle, a well connected with said constant level chamber and said nozzle, said nozzle being fed from said well slightly above the normal level therein, air being bled into said well slightly above such normal level, a second nozzle leading to the carbureting chamber adjacent the throttle, from said well at a point below the fuel level therein, and another well communicating with the atmosphere and fed from said constant level chamber by a restricted passageway and adapted to supply fuel to said first mentioned nozzle.
2. In a carburetor, a carbureting chamber having an air inlet, and a mixture out-

let, a throttle valve in said outlet, a constant level chamber supplying liquid level, a fuel nozzle, a well connected with said constant level chamber and said nozzle, said nozzle being fed from said well slightly above the normal level therein, air being bled into said well slightly above such normal level, a second nozzle leading to the carbureting chamber adjacent the throttle, from said well at a point below the fuel level therein, and another well communicating with the atmosphere through a regulable air inlet and fed from said constant level chamber by a restricted passageway and adapted to supply fuel to said first mentioned nozzle.

3. A carburetor having a primary venturi, a secondary venturi extending within the primary venturi, a feed channel extending into the secondary venturi, a constant level reservoir, a plurality of fuel passages fed by said constant level reservoir and discharging into said feed channel, and a regulable air inlet for said feed channel.

4. A carburetor having a primary venturi, a secondary venturi projecting into the primary venturi, a constant level reservoir, a collecting chamber and an atmospheric well both located at one side of the secondary venturi and both connected to the constant level reservoir and having a common air bled outlet in the second venturi, substantially as described.

In testimony whereof, I have hereunto set my hand.

FRANCOIS BAVEREY.
